(57) **CLAIM**

The ornamental design for a spray head, as shown and described.

DESCRIPTION

FIG. 1 is a perspective view of a spray head.

FIG. 2 is a front elevational view of the spray head of FIG. 1.

FIG. 3 is a rear elevational view of the spray head of FIG. 1.

FIG. 4 is a top plan view of the spray head of FIG. 1.

FIG. 5 is a bottom plan view of the spray head of FIG. 1.

FIG. 6 is a left elevational view of the spray head of FIG. 1; and,

FIG. 7 is a right elevational view of the spray head of FIG. 1.

The broken line showing of the threaded portion of the spray head is included for the purpose of illustrating and forms no part of the claimed design.
